UNITED STATES PATENT OFFICE.

CHARLES I. FURBISH, OF AMESBURY, MASSACHUSETTS.

STEM WINDING AND SETTING MECHANISM FOR WATCHES.

1,354,179.

Specification of Letters Patent. Patented Sept. 28, 1920.

Application filed April 22, 1920. Serial No. 375,737.

To all whom it may concern:

Be it known that I, CHARLES I. FURBISH, a citizen of the United States, residing at Amesbury, in the county of Essex and State 5 of Massachusetts, have invented certain new and useful Improvements in Stem Winding and Setting Mechanism for Watches, of which the following is a specification.

Pendent set and winding watches are usually wound by a forward rotary movement 10 of the stem, the backward movement of the stem idling. This results in a strain on the winding mechanism and an unnecessary wear thereof because of the lost motion besides consuming some considerable time in 15 the winding operation when the spring is fully run down.

The present invention provides for a positive winding of the spring at each forward and backward rotation of the stem 20 when the winding mechanism of the watch is thrown into gear, thereby avoiding unnecessary movement, wear, strain and loss of time.

25 The drawings illustrate a preferred embodiment of the invention. However, it is to be understood that in adapting the same to meet different conditions various changes in the form, proportion and minor details of 30 construction may be resorted to without departing from the nature of the invention as claimed hereinafter.

Referring to the drawings hereto attached:—

35 Figure 1 is a rear view of a watch movement provided with stem winding and setting mechanism embodying the invention, and showing the parts in position for winding the spring.

40 Fig. 2 is a view similar to Fig. 1 showing the relation of the parts when the winding mechanism is thrown out of gear and the setting mechanism is thrown into gear.

Fig. 3 is a sectional detail of the stem 45 winding and setting mechanism showing the parts on a larger scale.

Fig. 4 is a sectional detail on the line 4—4 of Fig. 1 illustrating the parts on a larger scale.

50 Fig. 5 is a sectional detail on the line 5—5 of Fig. 4.

Fig. 6 is a detail section on the line 6—6 of Fig. 4, looking in the direction of the arrow.

55 Corresponding and like parts are referred to in the following description and indicated

in the several views of the drawings by like reference characters.

The watch movement illustrated may be of ordinary construction and comprises the 60 usual bow or drum 1 which receives the operating spring. The bow or drum 1 is toothed as indicated at 2 to coöperate with a detent 3 and a winding gear 4. The winding gear 4 is provided with crown teeth 5 which are in mesh with pinions or gear elements 6 and 7 which are disposed at diametrically opposite points and receive a reverse movement. The pinions or gear elements 6 and 7 occupy a relative fixed position and are in mesh with the crown teeth 5 of the gear wheel 4 at all times. The gear wheel 4 is likewise in mesh with the teeth 2 of the barrel or drum 1 at all times. A shaft 8 passes through the gear elements 6 70 and 7 and the latter are loose thereon whereby the shaft 8 may rotate in either direction without imparting any movement to either one of the gear elements 6 or 7. Clutch members 9 and 10 are mounted upon the 80 shaft 8 and are rotatable therewith and are free to move thereon toward and away from the respective gear elements 6 and 7. The faces or sides of the clutch members 9 and 10 adjacent the respective pinions or gear elements 6 and 7 are provided with ratchet teeth which are adapted to mesh with corresponding ratchet teeth formed on the adjacent sides or faces of the respective pinions or gear elements. The ratchet teeth between the elements 6 and 9 face in an opposite direction to the ratchet teeth formed on the adjacent faces of the elements 7 and 10 so that when one set of teeth is in action to effect rotation of the winding gear 4, the 85 other set of ratchet teeth is idling or riding one upon the other. It will thus be understood that the winding gear 4 is positively rotated at each forward and backward rotation of the shaft 8. The portions of the 100 shaft 8 receiving the elements 9 and 10 are of non-circular form in cross section and the openings in the clutch members are of like formation so that the parts 9 and 10 rotate positively with the shaft 8 but are free to 105 move thereon toward and away from the respective gear elements 6 and 7.

A yoke 11 is pivotally mounted intermediate of its ends upon the front plate of the watch movement and is disposed to one 110 side of the winding gear 4. Spring arms 12 and 13 project laterally from the yoke 11 in

the same direction and their free ends engage annular grooves formed in the respective clutch members 9 and 10. The spring arms 12 and 13 serve to yieldably hold the teeth of the clutch members 9 and 10 in engagement with the teeth of the respective elements 6 and 7 so that when one set of teeth is in active operation to effect rotation of the winding gear 4, the other set of teeth is idling or riding one upon the other. A spring 14 co-acts with the yoke 11 to normally hold it in a given position with the clutch members 9 and 10 out of engagement with the respective gear elements 6 and 7.

15 Figs. 2 and 3.

The shaft 8 is centrally bored to receive a stem 15 which projects beyond the ends thereof as indicated most clearly in Fig. 4. The stem 15 is freely movable in the shaft 8 and its lower end is adapted to engage one end of a lever 16 which is pivotally mounted midway of its ends, the opposite end of the lever 16 engaging the lower end of the yoke 11. When the stem 15 is pressed inward the lever 16 is operated to effect a movement of the yoke 11 whereby the spring arms 12 and 13 are moved so as to throw the clutch members 9 and 10 into clutched engagement with the respective gear elements 6 and 7. Fig. 1. The numeral 17 designates the usual pendent which, in the present instance, engages the outer end of the shaft 8 and has sliding engagement therewith. The outer end of the stem 15 enters an opening in the inner end of the pendent 17. Fig. 4. Under normal conditions, the pendent 17 is moved outward thereby relieving the lever 16 of any controlling influence of the stem 15 with the result that the yoke 11 under the influence of the spring 14 assumes a position to throw the clutch members 9 and 10 out of engagement with the respective elements 6 and 7 as shown most clearly in Fig. 3. When the pendent 17 is pressed inward, it engages and effects a corresponding inward movement of the stem 15 whereby the lever 16 is operated and causes the yoke 11 to move whereby to throw the clutch members 9 and 10 into engagement with the respective pinions or gear elements 6 and 7. The spring may now be wound at each forward and backward rotation of the stem as will be readily understood.

55 The lower face of the clutch member 10 is provided with crown teeth 18 which, through the instrumentality of an intermediate train of gearing 19, the hands of the watch are adapted to be set in a manner well understood. When the winding mechanism is in gear, as shown most clearly in Figs. 1 and 4, the setting mechanism is out of gear and vice versa.

Having thus fully described my invention

what is claimed as new and desired to secure 65 by Letters Patent, is:—

1. A winding mechanism for a time movement the same comprising a winding gear, an operating stem and intermediate gearing between the winding gear and operating stem and embodying a ratchet connection whereby a continuous winding may be effected by a forward and a backward rotation of the operating stem.

2. A winding mechanism for time movements comprising a winding gear, a shaft, gear elements loose on the shaft and having a meshing engagement with the winding gear and clutch members in co-operative relation with the gear elements and having a reverse ratchet engagement therewith whereby a continuous winding may be effected by a forward and a backward rotary movement of the shaft.

3. A winding mechanism of the character specified, comprising a winding gear, a shaft, gear elements loose on the shaft and in mesh with the winding gear at diametrically opposite points and clutch members mounted on the shaft to rotate therewith and having a limited longitudinal movement thereon and having reverse ratchet engagement with the respective gear elements whereby to effect a continuous positive rotary movement of the winding gear at each 85 forward and backward rotation of the shaft.

4. In winding mechanism of the character specified, a winding gear, a shaft, gear elements loose on the shaft and in meshing engagement with the winding gear 100 at diametrically opposite points, clutch members mounted on the shaft to rotate therewith and having a limited longitudinal movement thereon and having reverse ratchet engagement with the respective gear 105 elements, spring means in co-operative relation with the gear elements to yieldably hold them in a given position and manually operable means for moving the clutch members into desired position whereby a continuous 110 winding may be effected by forward and backward rotation of the shaft.

5. In winding mechanism of the character set forth, a winding gear, a shaft, gear elements loose on the shaft and in meshing engagement with the winding gear at diametrically opposite points, clutch members loose on the shaft and rotatable therewith and having reverse ratchet engagement with the respective gear elements, spring means 115 co-acting with the clutch members to yieldably hold them in engagement with the respective gear elements and a manually operable stem loosely mounted in the shaft and adapted to effect movement of the clutch 120 members.

6. A winding mechanism substantially as herein set forth, comprising a winding gear,

gear elements in coöperative relation with the winding gear and disposed at diametrically opposite points, each including a ratchet mechanism, the one being the reverse 5 of the other, a yoke, spring arms projecting from the yoke and engaging the relatively movable parts of the aforesaid gear elements, and means for operating the yoke to throw the gear elements into coöperative 10 engagement.

7. Winding mechanism of the character set forth, comprising a winding gear, a shaft, gear elements loose on the shaft and in meshing engagement with the winding 15 gear at diametrically opposite points, clutch

members rotatable with the shaft and loose thereon, a pivoted yoke, spring arms projecting from the yoke and engaging the clutch members, the latter having reverse ratchet engagement with the respective gear 20 elements and a manually operable part for actuating the yoke to yieldably hold the clutch members in ratchet engagement with the respective gear elements.

In testimony whereof I affix my signature 25 in presence of two witnesses.

CHARLES I. FURBISH.
